UNITED STATES PATENT OFFICE.

MARK CROSBY, OF WAKEFIELD, MASSACHUSETTS.

WARDROBE-BEDSTEAD.

SPECIFICATION forming part of Letters Patent No. 283,991, dated November 2, 1880.

Application filed October 14, 1879.

To all whom it may concern:

Be it known that I, MARK CROSBY, of Wakefield, in the county of Middlesex and State of Massachusetts, have invented certain new and useful Improvements in Wardrobe-Bedsteads, of which the following is a specification, reference being had to the drawings accompanying this specification and forming part of the same, in which—

- 10 Figure 1 is a perspective view showing the parts closed so as to represent a cabinet. Fig. 2 is a perspective view showing the bed extended. Fig. 3 is a section taken from front to rear vertically, showing the parts together with the devices for producing automatic motion of portions of the case. Fig. 4 is a view, partly in section, showing the construction of the bed-case and the method of uniting and disconnecting the parts.
- 15 My invention consists in a certain construction and combination of parts, which will first be fully described, and then more fully specified and pointed out in the claims.

A in the drawings represents the casing of my cabinet-bed. This casing consists of two posts, B B, rising from a flooring or base-piece, G, to which said posts are detachably connected. To each post G an end piece, F, is attached by means of a metallic fastening-piece, f, screwed to the end piece, F, and engaging with corresponding openings in the back of the case, said openings being shown at f' in Fig. 4. The end pieces, F, are still further secured by dowels a a, which enter perforations in each end of the flooring G.

The posts B B may be connected by paneling C' C. The end pieces, F, contain open slots b, to receive the axial rod or bar upon which the bed turns when opened or closed.

40 To the upper part of the posts B B, I hinge the panels D D by means of spring-butts E, the tendency of the spring being to throw the panels into the position shown in Fig. 4. When in this position they form the sides of the casing when the bed is thrown up, as may be seen in Fig. 1, and also in Fig. 3, and, in connection with the other parts, they give the appearance of a highly-finished cabinet or secretary. When the bed is turned down into the position shown 45 in Figs. 2 and 3 these panels D D are auto-

50 matically turned upon the butts E into the position shown in said Fig. 2 and in broken lines in Fig. 3. This automatic action of said panels is secured in the manner following: The bed H being mounted upon the casing with its axis 55 or pivotal bearings c placed in the open slots b, wires or cords d are attached to eyes f' f', placed upon the end piece, K, of the bed-frame H. These wires pass directly from said eyes through an opening, g, in the back C', a small 60 friction-pulley being placed in said openings to secure easy action of the cord or wire. From the opening g the wire d passes upward and enters the casing at the point h, over a friction-pulley, and is carried thence to eyes e, 65 placed in the panels D.

The arrangement described is clearly shown in Fig. 3 of the drawings.

The operation of these parts is as follows: When the parts are in the position shown by 70 full lines in Fig. 3 it is evident that the cord or wire d will be relaxed, and the spring E upon the butt will be free to act and will throw the panels into position shown in said figure, and also in Figs. 1 and 4, where they will form part 75 of the sides of the casing. On the other hand, when the bed is turned down into the position shown in Fig. 2 and in broken lines in Fig. 3, the wire or cord d will draw the panels D D into the same plane with the back pieces, C C', where 80 they will form part of the head-board of the extended bed. This action, it must be understood, is wholly automatic, the spring-butts E turning the panels in one direction while the wire d draws them in the other. 85

In order to assist the motion of the bed H upon its axis e, I place weights L M in its extremity, one being located upon one side of the vertical plane within which the axis e lies and the other upon the other side of said plane. 90 When the bed is first raised both weights operate to assist in elevating the bed-frame.

Having thus fully described my invention, what I claim as new, and desire to secure by Letters Patent of the United States, is— 95

1. A wardrobe-bedstead to the fixed frame of which are hinged two panels, which are connected by springs to the frame and by cords or wires to the bedstead pivoted to the frame, by which combination of parts the panels are, 100

when the bedstead is raised, pressed outward by the springs to form the sides of the wardrobe, and when the bedstead is lowered are drawn in by the cords to form a part of the head-board, substantially as set forth.

2. The combination, with the pivoted bed H, of two panels hinged by spring-butts to the upright casing and connected, by mechanism substantially as described, with the pivoted bed, said panels being automatically swung into position to form part of the continuous head-board when the bed is lowered, and thrown outward when the bed is raised, to form part of the sides of the upright case, substantially as set forth.

3. The combination, with the pivoted bed H, of the hinged panels D D, actuated in one direction by suitable springs, the wires or cords

d, and the skeleton-case, all as and for the purpose set forth.

4. The combination of the pivoted bed, the panels D D, spring-butts E, wires or cords d, and the casing A, all as and for the purpose set forth.

5. A wardrobe or cabinet bedstead consisting of the detachable casing B F G, the panels D D, the pivoted bed H, weights L M, and wires d d, as and for the purpose set forth.

In testimony whereof I have signed my name to this specification in the presence of two subscribing witnesses.

MARK CROSBY.
